UNITED STATES PATENT OFFICE.

ARTHUR F. POOLE, OF CHICAGO, ILLINOIS, ASSIGNOR TO THE WAHL COMPANY, OF WILMINGTON, DELAWARE, A CORPORATION OF DELAWARE.

CALCULATING-MACHINE.

1,274,572.

Specification of Letters Patent.

Patented Aug. 6, 1918.

Application filed February 24, 1914. Serial No. 820,602.

To all whom it may concern:

Be it known that I, ARTHUR F. POOLE, a citizen of the United States, residing at Chicago, in the county of Cook and State 5 of Illinois, have invented certain new and useful Improvements in Calculating-Machines, of which the following is a specification.

My invention is an improvement in calculating machines, particularly in the type 10 of calculating machines used with a typewriter, one example of which is the machine described in Patent #893,719 issued to John C. Wahl, July 21st, 1908. More specifically, 15 my machine is an improvement in calculating machines of the above mentioned type used for the calculation of numbers in systems other than the decimal system, such for instance, as calculations involving English 20 money, which has a table as follows:

12 pence	-----	1 shilling
20 shillings	-----	1 pound

Another example of a table other than the 25 decimal system is the Indian currency table of pies and annas, as follows:

12 pies	-----	1 anna
16 annas	-----	1 rupee

30 It will be observed that in the two tables mentioned above, there arises the necessity of inserting a number larger than 10 in the totalizer, such for instance, if one wished to insert 11 pence in the English table, or 14 35 annas in the Indian currency table given above. In Patent #893,720, to Hyman Eli Goldberg, is disclosed a method of handling numbers of this kind. The actuator is provided with a special key printing 1, and 40 revolving the master wheel 10 spaces, thereby inserting 10 in the totalizer and printing 1 on the work sheet. This special key is used in the following way:

Assume one to be working with a totalizer 45 in the English money table, and that one wishes to insert 11 pence into the totalizer. The totalizer is brought to the tens place of the pence denomination, and the special key is operated. This prints 1 on the work sheet 50 and inserts 10 units into the totalizer. The totalizer then escapes to the unit's decimal

place of the pence denomination, and the 1 key is operated. This key inserts 1 in the totalizer and prints 1 on the work sheet to the right of the 1 previously printed. As a 55 result of these operations, 11 is printed on the work sheet and 11 is inserted in the totalizer.

It is apparent that with the arrangement described above, there exists some liability 60 of confusion or mistake due to the fact that the operator has two keys on her typewriter, which print 1, viz., the ordinary numeral key and the special key. It has been customary to distinguish these keys by making 65 the 1 printed by the special key, which it will be remembered inserts 10 into the totalizer, have a characteristic type differing in appearance from that on the 1 key, but nevertheless, the fact remains that when the 70 totalizer is in the tens decimal place of the pence denominations, either key printing 1 may be operated, and if the ordinary key is operated in this place, an erroneous calculation results.

It is one of the objects of my invention to so interlock the special key above referred to, and the ordinary 1 key that when the totalizer is in a position requiring the use of the special key, the ordinary 1 key, and in 80 fact all the other numeral keys of the calculating machine, are locked, and on the other hand as soon as the totalizer moves from the decimal place requiring the use of the special key, the special key itself is locked, and all the other numeral keys are unlocked. In my pending application for improvements in calculating machines #809,932, filed January 2nd, 1914, I have shown one form of lock which performs the above recited function, and this lock has been shown in connection with a totalizer adapted to calculate in the long ton table. My present invention is in the nature of an improvement 85 upon or variation from the special key lock shown in the above entitled application, and is shown in connection with a totalizer adapted to calculate in the Indian currency table, one adapted to calculate in the English money table, and one adapted to calculate in the ordinary decimal table. The device shown in my present application is 90 95 100

adapted to coöperate with totalizers of all these tables.

A further object of my invention is to provide an interlock for numeral keys which shall be very simple in its construction and positive in its action, and shall employ parts of the Wahl actuator which are already required for another function.

These and other objects of my invention are described in the accompanying specifications, in the drawings of which—

Figure 1 is a partial front elevation of a calculating machine equipped with my device,

Fig. 2 is a perspective view of the lock for the keys,

Fig. 3 is a side view taken along the section line 3—3 of Fig. 4,

Fig. 4 is a view taken along the line 4—4 of Fig. 3,

Fig. 5 is a plan view of the numeral keys.

I have shown my invention as applied to the calculating machine described in the cited patent to Wahl. Since the Wahl machine contains a large number of parts which are not material to the understanding of my present invention, and would only confuse the description thereof, I have omitted showing these parts in the drawings, and shall not enter into any particular description of them. Reference may be had to the cited patent to Wahl where the operation of this adding and subtracting attachment is thoroughly described.

I shall premise that there is a typewriter equipped with a Wahl adding and subtracting attachment, and that this attachment is operated by the keys 11, which print the numbers 1, 2, 3, 4, 5, 6, 7, 8, and 9 and insert like numbers into the totalizers 12, 13, and 14, which are mounted on a truck 15, which travels step by step through the actuation of the keys 11. The calculating attachment is also provided with a special key which I number 16, and this key is so arranged as to print a 1 on the worksheet and simultaneously insert 10 into any totalizer which may be in a position to be actuated thereby. It will be observed in Figs. 1 and 3 that each of the numeral keys 11 and the special key 16 are connected by a pull rod 17 to fans 18 and 18' in the actuator. Consequently the operation of any of these keys results in the rotation of the connected fan. These fans 18 and 18' coöperate with a single key mechanism best shown in the rear view of Fig. 4, the object of this mechanism being to prevent the simultaneous operation of more than one key. It consists of a series of cams 19 and 21 pivoted in the frame work at 20. The cam 19 on the extreme right has a pin 25 rigidly attached thereto, which moves in a slot 26 in the

frame work 9. This constrains the motion 65 of the cam 19 to the right. The cam on the extreme left, which cam I have numbered 21, is provided with a pin 22, rigidly attached thereto, and which pin coöperates with the slot 23 in a link 24. When the 70 parts are in the position shown in Fig. 4, it will be seen that there is a space equivalent to the width of one of the fans 18 between the set of cams from their extreme left hand position as determined by the position of the cam 21, to the extreme right hand position as determined by the position of the right hand cam 19. Consequently any of the fans numbered 18 may be operated, but no two of these fans may be operated at one time. 75 The fan numbered 18' is the one which is connected to the special key 16. It will be observed that when the parts are in the position shown in Fig. 4, the position of the cam 21, as held by the slot 23, is such that 80 the operation of this fan 18', and consequently the special key 16 attached thereto, is prevented. Also that the operation of any of the fans 18, and consequently the keys 11 attached thereto, is permitted. 85 Now, suppose the link 24 is depressed. The pin 22 will then engage the upper portion of the slot 23 and the cam 21 will be thrown to the right. This will close the gap in the single key mechanism between the pin 25 90 and the pin 22, thereby preventing the operation of any of the fans 18, and will free the fan 18' and its connected special key 16. 95

It is obvious that the lowering of the link 24 will lock all the keys 11 and unlock the special key 16, and the returning of this link 24 to its original position as shown in Fig. 4, will lock the special key 16, and unlock all the keys 11. It remains therefore but to describe the mechanism connecting this link 24 with the position of the totalizers on the carriage to accomplish the results set forth in the beginning of this specification. This will now be done. 100

Pivoted to the frame work at 27 is a lever 28, which is pivoted to the link 24 by the stud 29. In the other end of this lever 28 is a pin engaging a fork in a lever 31, rigidly attached to a shaft 32, which is pivoted in the frame work; a spring 33 between the lever 31 and the frame work 9 serves to hold the chain of mechanism including the levers 28 and 31, and the link 24 in a normal position determined by the contact of the pin 22 on the lower end of the slot 23. 110 To the front end of the shaft 32 (shown in Figs. 1, 2, and 3) is attached an arm 34 carrying a roller 35, which roller coöperates with cams 36 and 37 on the totalizers 12 and 13. It will be observed that cam 36 115 has projections 38 and 39, and cam 38 has projection 40. These projections are of proper length to depress the roller 35 suffi- 120 125

ciently to lower the link 24 to its alternative position, thereby unlocking the special key 16, and locking the numeral keys 11 when said projections 38, 39 and 40 are in contact with the roller 35.

In Fig. 1, I have shown three totalizers, 12, 13 and 14 upon the totalizer truck 15. Totalizer 12 is adapted to calculate in the Indian currency table, that is, 12 pies equal one anna, 16 annas equal one rupee. In this table there are two places in which the special key may be required to be used, that is, in the tens decimal place of the pie denomination and in the tens decimal place of the anna denomination. By providing the two projections 38 and 39 on the cam 36, I unlock the special key 16 at these two points and lock the keys 11. At any other point on this totalizer, the key 16 is locked and the keys 11 are unlocked.

The totalizer 13 is shown as calculating in the English money table, which is, 12 pence make one shilling, 20 shillings make one pound. There is but one place on this totalizer in which the special key is required to be operated, that is, in the tens place of the pence denomination. I therefore show one projection 40 on the cam 37 attached to this totalizer.

30 Totalizer 14 is adapted to calculate in the ordinary decimal system, in which system the special key 16 will never be required to be used. I therefore show the cam 41 attached to this totalizer without any projection. Consequently the special key is always locked, and the ordinary keys 11 are always unlocked.

From what has been said, it will be obvious that all the Wahl calculating machines 40 could be provided with this special key 16, and that this special key would be inoperative except a totalizer were used having projections to engage the roller 35, in which case, the special key would be free to operate in the particular position of the totalizer as determined by the cam associated therewith. I also wish to call attention to the fact that the interlock described in this present application may be used to advantage 50 with the device forming the subject of my co-pending application above referred to.

Many changes and variations may be made in the precise form and device shown in this application without departing from the 55 spirit thereof, since I claim:

1. In a calculating machine the combination of: a set of numeral keys; a single key locking mechanism comprising a group of shiftable cams acted on by said numeral keys; and means independent of said numeral keys for shifting one of said cams to an alternative position.

2. In a calculating machine the combination of: a set of numeral keys divided into

two parts; a single key locking mechanism 65 including a set of cams acted on by said numeral keys; and means for shifting one of said cams to lock all of said keys comprising one of said parts.

3. In a calculating machine the combination of: a set of numeral keys divided into 70 two parts; a single key locking mechanism including a set of cams acted on by said numeral keys; and means for shifting one of said cams to lock the keys in either of 75 said parts.

4. In a calculating machine the combination of: a set of numeral keys divided into 80 two parts; a single key locking mechanism including a set of cams acted on by said numeral keys; and means for shifting the cam between said parts to thereby lock all of the keys in one or the other of said parts.

5. In a calculating machine the combination of: a set of numeral keys divided into 85 two parts; a single key locking mechanism including a set of cams acted on by said numeral keys; a traveling element; and means controlled by said traveling element for shifting one of said cams to lock all of 90 said keys comprising one of said parts.

6. In a calculating machine the combination of: a set of numeral keys divided into 95 two parts; a single key locking mechanism; a set of cams acted on by one of said numeral keys; a traveling element; and means controlled by said traveling element for shifting one of said cams to lock the keys in either of 100 said parts.

7. In a calculating machine the combination of: a set of numeral keys divided into 100 two parts; a single key locking mechanism; a set of cams acted on by said numeral keys; a traveling element; and means for shifting the cam between said parts to thereby lock all of 105 said keys in one or the other of said parts.

8. In a calculating machine the combination of: a set of numeral keys divided into 110 two parts; a single key locking mechanism including a set of cams acted on by said numeral keys; a traveling element controlled by said numeral keys; and means controlled by said traveling element for shifting one of 115 said cams to lock all of said keys comprising one of said parts.

9. In a calculating machine the combination of: a set of numeral keys divided into 120 two parts; a single key locking mechanism; a set of cams acted on by one of said numeral keys; a traveling element controlled by said numeral keys; and means controlled by said traveling element for shifting one of said cams to lock the keys in either of 125 said parts.

10. In a calculating machine the combination of: a set of numeral keys divided into two parts; a single key locking mechanism;

4
a set of cams acted on by said numeral keys; a traveling element controlled by said numeral keys; and means controlled by said traveling element for shifting the cam between said parts to thereby lock all of said keys in one or the other of said parts.

In witness whereof, I have hereunto sub-

scribed my name in the presence of two witnesses.

ARTHUR F. POOLE.
